FEEDING MECHANISM

John M. Clark, Detroit, Mich., assignor to
Universal Button Fastening & Button Com-
pany, Detroit, Mich., a corporation of Michigan

Application March 11, 1931, Serial No. 521,637
In Canada September 28, 1929

12 Claims. (Cl. 218—12)

This invention relates to button and button fastener feeding mechanism for button attaching machines and the like, and among other objects aims to improve the utility and efficiency of mechanism of this character.

The nature of the invention may be readily understood by reference to a machine embodying the same and illustrated in the accompanying drawings.

10 In said drawings:

Fig. 1 is a perspective of a button attaching machine embodying the inventive feeding mechanism;

15 Fig. 2 is a vertical central section through the button and fastener feeding hoppers and associated mechanism;

Fig. 3 is a section taken along the plane 3—3 of Fig. 2 showing a portion of the interior of the fastener hopper and fastener raceway;

20 Fig. 4 is a section of the button hopper taken on the plane 4—4 of Fig. 2;

Fig. 5 is an enlarged elevation of a detail of the periphery of the rotary element in the button hopper showing the button outlets;

25 Fig. 6 is a similar elevation showing fastener outlet passages in the fastener hopper;

Fig. 7 is a vertical section similar to that shown in Fig. 2 of a different form of feeding mechanism;

30 Fig. 8 is a plan section taken on the plane 8—8 of Fig. 7 showing a detail of a hopper adjusting device;

Fig. 9 is an elevation, partly in section, showing a hopper clutch; and

35 Fig. 10 is a perspective view of a hopper latch bar.

The inventive feeding mechanism is here shown embodied in a button attaching machine to supply buttons and fasteners through raceways 11 and 12 to button attaching mechanism indicated generally at 13.

In the present arrangement, fasteners which embody heads and attaching prongs are supplied from a fastener hopper indicated at 14 and comprising a rotary conical shaped hopper member 15 which, with the recess 16 in the stationary frame of the machine, provides an enclosure for the fasteners. The rim 18 of the rotary member fits with the circular mouth 17 of the stationary structure sufficiently closely to exclude fasteners. The edge of the rotary member 15 is spaced a distance indicated at 19 from the opposite face of the stationary portion of the hopper to provide a passage for the heads of the fasteners; and 55 to assure the discharge of the fasteners with their

heads arranged flat-wise. The edge of the rotary member is provided with a series of apertures 20 which permit the escape of fasteners only when arranged so that the prongs thereof pass through the apertures and the heads through the space 19. 60 In such predetermined position the fasteners indicated at 21 may pass down the raceway 12 which is arranged tangentially with the rim of the rotary member 15 and which has a slot 22 through which the fastener legs extend. The 65 present fastener hopper is designed to permit the passage of double pronged fasteners and the slot 22 maintains the prongs in alignment for proper delivery to the placing and attaching mechanism.

The rotary hopper member 15 is mounted for 70 rotation upon a drive shaft 24 which passes through an opening in the hub 25 of the hopper. As shown the hub 25 abuts against the stationary hub 26 to assure the maintenance of an adequate space 19 for the passage of the fastener 75 heads. The upper member 15 is made longitudinally outwardly slidable on shaft 24 to permit discharge of the contents of the hopper and the outer wall of the rotary hopper is recessed as at 27 for this purpose. The hopper is keyed to 80 the shaft to effect its rotation by a pin 28 engaging in one of a series of recesses or ratchet notches 29 in a driving element 30 secured to and associated with the stop 31 which is pinned at 32 to the shaft. Engagement of the pin 28 85 with the face of the stop 31 prevents outward movement of the hopper during operation, and when the pin 28 is withdrawn, the engagement of the wall of the recess 27 with the stop 31 limits the outward travel of the hopper. Quick 90 detachment of the hopper from the shaft is effected by making the pin 28 longitudinally slidable in the hopper 15 and pressing it into a notch 29 by means of a spring 33 which is confined between the collar 34 on the pin and the 95 removable plug 35. Thus when the pin is withdrawn so that it clears the stop 31 the hopper is not only disconnected from the driving shaft but it may be moved outwardly to discharge its contents. In order to empty the hopper it is 100 not necessary, therefore, to run the fasteners through the machine with the possibility of distortion or mutilation. This is particularly desirable because one machine may employ a variety of fasteners of the same size which vary 105 as to style of head and plating or coating. Rotation of the hopper is effected by sprocket chain 36 which passes around a sprocket on drive shaft 24. In the event a fastener should become 110 jammed between the stationary and movable

portions of the hopper, the excess driving resistance causes the pin 28 to be cammed out of its recess (by reason of the rounded end of the pin), thus releasing the drive and avoiding further damage. Moreover the depth of the notches 29 is not sufficient to prevent rotation of the hopper by hand independently of the rotation of the shaft in the event it should become necessary to dislodge an improperly placed fastener, or for other reasons. During such manual operation of the hopper, the pin or catch 28 merely rides in and out of the successive notches 29.

Buttons are supplied from a similar though somewhat differently shaped hopper 37 advantageously operated by the same shaft 24 and located on the opposite side of the machine. The space 38 between the stationary portion of the hopper structure and the rotating hopper element 39 is, of course, adjusted to permit the passage of the button heads and the adjacent rim of the hopper member 39 is formed with passages 40 shaped to permit the passage of the collet or neck portion of the button. Thus buttons can escape only when arranged with their heads in the space 38 and their collets or necks in one of the passages 40 on the rotary hopper member 39. In this position they may pass out into the button raceway 11 which is arranged tangentially to the hopper. The buttons are held in the raceway in a predetermined position and in such predetermined position are delivered to the button placing and attaching mechanism.

The rotary hopper member 39 is detachably keyed to shaft 24 by devices similar to those described in connection with the fastener hopper, and the former may be easily drawn outwardly on the shaft to effect a quick discharge of the buttons. Quick discharge of the buttons is even more important than the fasteners inasmuch as the variety of buttons of the same size attached by a given style of machine may be very great and it is very important to avoid such marring of the buttons as would occur if it were necessary to pass the buttons through the machine in order to discharge the hopper. Aside from the inevitable marring of the buttons by the latter operation, it would also be very time consuming.

Filling of the button and fastener hoppers may be effected through passages 41 and 42 normally covered by the hinged covers 43 and 44.

In Figs. 7 to 10, inclusive, is illustrated a different form of fastener and button hopper mechanism embodying additional features not shown in the arrangement previously described. In this arrangement the fastener and button hoppers 45 and 46, respectively, are driven from shaft 47 through a ratchet device 48 which permits rotation of the hoppers in their normal direction of rotation independently of the drive of the shaft or at a rate faster than such drive by manually spinning the hoppers. Among other advantages, the facility for such independent rotation permits the supply of fasteners and buttons to fill empty or insufficiently filled raceways without running the entire machine and possibly wasting some buttons and fasteners at the attaching dies. The ratchet arrangement also makes it convenient to design the hopper drive to operate only while the machine is actually attaching buttons and not during idle periods of the attaching mechanism when the driving motor may nevertheless be running. In such cases, upon stopping the attaching mechanism the inertia in the rotating hoppers is spent mere-

ly in a short continued rotation and is not transmitted back to the attaching mechanism with the possible result of moving the parts beyond their proper stopping position (i. e. with the attaching dies open or separated). With this sort of hopper drive, marring of the buttons through excessive rotation of the hopper is avoided.

The ratchet drive comprises a pair of ratchet elements 49 and 50 having interfitting ratchet teeth, the former loose upon and the latter pinned to drive shaft 47. The ratchet element 49 is maintained in yielding engagement with the companion element 50 by a spring 51 carried between it and a shoulder 52 on the hub 53 of the rotating hopper, with which the ratchet element is drivingly connected by a tongue 54 slidably operating in a slot 55. A space 56 is allowed between the members to permit the retraction of the ratchet 49 sufficiently to clear the ratchet teeth on the element 50. A cover sleeve 57 closely surrounds the ratchet mechanism to exclude buttons, fasteners and other foreign matter.

The rotary hoppers may be moved outwardly to discharge buttons or fasteners or to release a "jam"; and for this purpose a latch 58 is provided on each hopper cone for quickly releasing the hopper. A spring 59 normally presses the end 60 of the latch into a groove 61 on the shaft 47. The engagement of the latch in groove 61 not only prevents outward movement of the hopper but maintains the proper space 63 between the rotary portion of the hopper and the stationary structure and through which the heads of the buttons or fasteners escape. Proper adjustment of this space to the thickness of button or fastener heads is effected by rotating the eccentric bushing 64 through which the latch 58 passes and thereby moving the rotating portion of the hopper in or out relatively to the stationary portion. A set screw 65 maintains the adjustment.

The hopper may be released as aforesaid by raising the latch through its handle 66 until it clears groove 61. The outward movement of the hopper is limited by a stop in the form of a headed rod 67 whose head 68 engages the face of the hopper and whose inner end 69 is made larger than the plug 70 screwed into the hopper drive shaft 47 through which the rod passes. A spring 71 confined between the enlarged end 69 of the rod and the plug 70 normally tends to move the hopper inwardly. When moved outwardly on the shaft, separation between the driving elements occurs at the ratchet but the cover sleeve 57 is long enough to prevent fasteners or buttons from reaching the ratchet device.

The shaft 47 is driven by a sprocket chain 72 which passes around sprocket 73. Sprocket 73 is frictionally held between plates 74 and 75, the latter being faced with a friction facing 76. The plates are clamped together to effect an adequate frictional engagement with the sprocket by screws 77. The frictional engagement with the sprocket is sufficient to insure rotation of the hoppers under ordinary conditions, but if a button or fastener jams in the hopper mechanism, damage to the machine is avoided by slippage of the driving sprocket 73.

The hoppers may be filled through the passages 78 and 79, respectively, which are provided with covers, not shown.

The subject matter of the hopper mechanism illustrated in Figs. 1 to 6, inclusive has been di-

vided from my copending application Serial No. 565,420, filed June 2, 1922, and the subject matter of the hopper mechanism shown in Figs. 7 to 10, inclusive, has been divided from my copending application Serial No. 30,686, filed May 16, 1925.

Obviously the invention is not limited to the details of construction herein shown and described since these may be variously modified. Moreover it is not indispensable that all features of the invention be used conjointly, since all features may be advantageously employed in various combinations and subcombinations.

Having described my invention, I claim:

1. In a machine of the character described, the combination comprising a feeding hopper having a rotary portion whose free edge is spaced from the fixed portion of said hopper to provide a space for the discharge of articles from said hopper, and an eccentric adjusting pin for moving said

20 rotating portion to adjust the width of said space.

2. In a button attaching machine, the combination of a hopper, driving mechanism therefor, including a drive shaft, and quickly detachable means for connecting the hopper to said drive shaft in direct driving relation therewith and which also keys the hopper thereon against longitudinal movement with respect to said drive shaft.

3. In an attaching machine of the character described, the combination comprising a hopper drive shaft, a rotary hopper mounted on said shaft and longitudinally slidable thereon, a device for connecting said hopper to said shaft and to hold the hopper against longitudinal movement on said shaft, and means for releasing said device to permit said hopper to be moved longitudinally on said shaft to discharge its contents.

4. In a machine of the character described, the combination comprising a stationary hopper housing, a hopper shaft, a rotary feeding hopper longitudinally slidable and spaced from said housing to provide an aperture for the feeding of articles from the hopper, a locking pin engaging said shaft for holding said hopper in proper position on said shaft and releasable to permit said hopper to slide outwardly on said shaft to discharge the contents of the hopper, and an eccentric bushing around said pin and rotatable to shift said pin relative to said hopper to adjust the feeding aperture.

5. In a machine of the character described, the combination comprising a stationary hopper housing, a hopper shaft, a rotary feeding hopper longitudinally slidable and spaced from said housing to provide an aperture for the feeding of articles from the hopper, a locking member for holding said hopper in proper position on said shaft and releasable to permit said hopper to slide outwardly on said shaft to discharge the contents of the hopper, and means for adjusting said lock inwardly or outwardly relative to said stationary hopper housing to vary the size of the feeding aperture.

6. In a machine of the character described, the combination comprising a hopper shaft, a rotary hopper slidable on said shaft and movable outwardly to permit the discharge of the contents of the hopper, a releasable lock for holding said

hopper in operative position on said shaft, a slide-able retainer for limiting the outward movement of said hopper, and a spring associated with said retainer for resiliently forcing said hopper inwardly.

7. In a machine of the character described, the combination comprising a rotating feed hopper, a driving ratchet therefor arranged to permit rotation of said hopper independently of its drive, and means for sliding said hopper on said shaft without interrupting its drive thereby to dis-charge the contents of the hopper.

8. In a machine of the character described, the combination comprising a rotating feeding hopper, a driving ratchet therefor inside said hopper and arranged to permit rotation of said hopper independently thereof, and a guard for said ratchet to protect the same from the contents of said hopper.

9. In a machine of the character described, the combination comprising a rotary hopper mounted on a shaft and slidable longitudinally thereof, a latch operable in a recess for holding said hopper in a definite position on said shaft and movable out of said recess to permit said hopper to be moved on said shaft to discharge its contents, a check to limit the movement of said hopper on said shaft, and a spring to return said hopper to normal position.

10. In a machine of the character described, the combination comprising a stationary hopper housing, a rotary hopper mounted on a shaft and slidable longitudinally thereof to withdraw the same from operative relation to its housing to permit the discharge of its contents, a stop to limit its movement on said shaft, and a spring to return it to normal position.

11. In a button attaching machine, the combination comprising a rotary shaft, hopper housings, a plurality of supply hoppers mounted to rotate on said shaft and being slidable outwardly relative to their respective housings to discharge their contents, said hoppers having apertures associated therewith constructed and arranged to permit the escape of articles therein when in predetermined position, means for rotating said shaft to drive the hoppers, means for detachably securing said hoppers to said rotary shaft in operative position and releasable to permit the outward movement of said hoppers, and means for limiting the outward movement of said hoppers to prevent complete detachment thereof.

12. In a button attaching machine, the combination comprising a rotary shaft, a supply hopper mounted to rotate coaxially with said shaft, said hopper having apertures associated therewith constructed and arranged to permit the escape of its contents when in predetermined position, means for rotating said shaft, and positive clutch means for securing said hopper to said rotary shaft whereby the latter may be positively rotated in one direction, said means automatically permitting the manual rotation of said hopper independently of the rotation of said shaft while maintaining the operative driving connection with the shaft.

JOHN M. CLARK.
